UNITED STATES PATENT OFFICE.

MORRIS WEINER AND GEORGE S. WEINER, OF CHICAGO, ILLINOIS; SAID MORRIS WEINER ASSIGNOR TO SAID GEORGE S. WEINER.

ADJUSTABLE GARMENT.

Application filed August 28, 1926. Serial No. 132,276.

The object of this invention is to provide a garment having an adjustable waist band of an improved construction, the same representing an improvement over that shown in our prior Reissue Patent Number 16,179. It is a further object of this invention to provide garments known as knickers with adjustable waist bands and adjustable knee bands both of our improved construction. The attainment of these and further objects will be apparent from the accompanying specification taken in conjunction with the drawings forming a part thereof.

Referring now to the drawings, Fig. 1 is a view of a garment showing a preferred embodiment of our invention; Figs. 2 and 3 are detail views of the adjustable waist portion and leg portion, respectively; Figs. 4 and 5 are views similar to Figs. 1 and 2 illustrating a modification.

In the drawings, 1 and 2 represent the front and rear portions of the garment, respectively, the two being sewed together at 3. The side pocket is indicated at 4 and the rear pocket at 5. The pocket edge 4 is in alignment with the edge 3, but is shown bulged forward to expose the usual inner strip 7, made of the same material as are the trousers, and to which the rear portion 30 of the lining of the pocket is attached (not shown) and to which is also attached the rear portion 2. The above construction thus far described is the usual construction in ordinary unadjustable trousers.

In our improved construction the portion 7 is not sewed to the rear portion 2 for its entire length but only up to the point 6 which is approximately at the hips of the wearer. At 6, between the forward and rear parts of the trousers is introduced a gore consisting of a single piece of material 8, sewed to the rear portion at 9 and to the front portion 1 and the portion 7, at 10. The portion 8 extends to the waist band 45 and consists of a triangular piece of material the apex of which may be removed from a trapezoid and the edges at that point sewed together at 11.

On the outside of the waist band is provided at the rear a hook 12 and at the front a number of eyelets 13, to any one of which the hook may be attached. The waist band may be adjusted in length by attaching the hook to different eyelets. A similar construction is provided on each side of the gar-

ment to give the proper adjustment while maintaining the front portion centered.

At the lower end of the garment an adjustable knee band is provided. This band is a continuous loop of material large enough to allow the foot to pass therethrough. At the lower part of the trousers is introduced a triangular or trapezoidal piece of material 18 similar to the strip 8 introduced above. This piece of material is sewed to the rear portion 2 at 19 and to the front portion 1 at 20. On the outside of the knee band is fastened a hook 12' and some eyelets 13' similar to those above and for a similar purpose.

It is to be noted that while in the adjustment of the waist line the rear portion folds forward overlapping the front portion, the opposite is true at the knee. This construction at the waist line allows the hand an unobstructed entrance at the pocket, while at the knee it is desirable to fold the forward portion backward to allow more freedom of the leg in a forward direction in obstructed places, such as amongst shrubbery and the like.

The modification shown in Figs. 4 and 5 differs from that shown in Figs. 1 and 2 in that the portion 8' while similar to 8 in shape is however integral with the rear portion 2 rather than being a separate piece. The fastening means is also different. In this construction there is provided a small narrow belt 12', and a button hole 31 through which the belt is passed. On the inner side of the garment there is provided a number of buttons 33 to which the belt is secured in adjustable relationship.

In compliance with the requirements of the statutes we have herein described a preferred embodiment of our invention. We do not however wish to be limited to the precise construction set forth, the same being shown for illustrative purposes only.

What we claim as new and desire to secure Letters Patent upon is:

1. A pair of trousers including an adjustable band continuous on the outside of the garment at the place of adjustment of the band, front and rear leg forming portions terminating at the band a short distance apart, a triangular gore terminating along the band between said front and rear portions and sewed to one of said portions, and means for adjusting the band by folding

less than all of the band portion at the gore.

2. A pair of trousers including an adjustable band, front and rear leg forming portions, a triangular gore of suiting material sewed along one of its three sides to said band between said front and rear portions, the other two sides of the gore joining said portions, said portions being sewed to each other lengthwise of the garment leg and the gore, and means for adjusting the band at the gore.

3. A garment front and rear portions sewed together lengthwise of the garment at the side thereof, a triangular gore having two sides of equal length between said portions one of said sides being sewed to the front portion the other to the rear portion, the third side of the gore being approximately equal in length to the other two, a band terminating said portions, said third side of the gore being sewed to the band, said band being adjustably foldable at the gore, and means for securing the band in any one of a plurality of positions.

4. A garment including an adjustable band, front and rear garment portions sewed to said band, said portions terminating at said band a short distance apart, at the side of the wearer, a triangular gore

sewed along an entire one of its sides to said band between said portions, said band being continuous at said gore, the other two sides of the gore joining said front and rear portions, said band being adjustable by folding the same at the gore, and means on the outside of the garment for holding the band in any one of a plurality of adjusted positions.

5. A garment including an adjustable waist band, front and rear garment portions sewed to the waist band, said portions terminating at said band a short distance apart and at the sides of the garment, two substantially equilateral triangular gores sewed to said band between said front and rear portions, one of said gores being on the right hand side of the wearer and the other on the left hand side, said band being continuous at said gores, said band being adjustable by folding the same at each of said gores, whereby the front of the garment is maintained centered, and means at each of the sides of the garment for holding the band in any one of a plurality of adjusted positions.

In testimony whereof we have hereunto affixed our signatures.

MORRIS WEINER.
GEORGE S. WEINER.
